UNITED STATES PATENT OFFICE.

LEWIS J. ATWOOD, OF WATERBURY, CONNECTICUT, ASSIGNOR TO THE PLUME & ATWOOD MANUFACTURING COMPANY, OF SAME PLACE.

DESIGN FOR A RESERVOIR OR OIL-POT FOR LAMPS.

SPECIFICATION forming part of Design No. 32,990, dated July 24, 1900.

Application filed May 26, 1900. Serial No. 18,163. Term of patent 14 years.

To all whom it may concern:

Be it known that I, LEWIS J. ATWOOD, a citizen of the United States, residing at Waterbury, in the county of New Haven and State of Connecticut, have invented and produced a new and original Design for Reservoirs or Oil-Pots for Lamps, of which the following is a specification, reference being had to the accompanying drawings, forming part thereof, in which—

Figure 1 is an elevation showing my new design, and Fig. 2 a sectional plan at $x x$ of Fig. 1 of a portion of the reservoir to show the configuration.

As shown in the drawings, the leading or material feature of my design consists of the vertically-disposed flutes or corrugations of the vertical sides of the reservoir or oil-pot of the lamp.

The vertical sides of the reservoir or oil-

pot are provided with a series of ribs *a* and grooves or depressions *b*, disposed or arranged vertically of the said sides, as shown in Fig. 1. The ribs and grooves forming the flutes or corrugations extend vertically of the reservoir 25 and all around upon the surface thereof.

The bottom of the reservoir is represented at *c* and the top at *d*.

What I claim is—

The design for a reservoir or oil-pot for 30 lamps, substantially as herein shown and described.

In testimony whereof I have signed my name to this specification in the presence of two subscribing witnesses.

L. J. ATWOOD.
